CLAIM

The ornamental design for a bracket for supporting a low pressure gas converter, as shown and described.

DESCRIPTION

FIG. 1 is an elevational view of a bracket for supporting a low pressure gas converter showing my new design; FIG. 2 is a elevational view from the opposite side of FIG. 1;

FIG. 3 is a elevational view as seen from the right end of FIG. 1;

FIG. 4 is a view as seen from the left end of FIG. 1;

FIG. 5 is a top plan view thereof; and

FIG. 6 is a bottom plan view thereof.
